UNITED STATES PATENT OFFICE.

FRANK E. WAKEFIELD, OF ELGIN, ILLINOIS, ASSIGNOR TO ILLINOIS WATCH CASE COMPANY, OF ELGIN, ILLINOIS, A CORPORATION OF ILLINOIS.

WATCH.

Application filed August 9, 1926. Serial No. 128,180.

My invention has to do with a case which is designed for the reception of a watch movement, and particularly with that type of article commonly known as a traveler's watch. The present improvements are in the direction of simplicity, security to the watch when the case is opened, greater accessibility to the watch movement in case of inspection, etc. Objects such as these are highly important in view of the deficiencies which characterize the present day watches of the type referred to.

An illustrative embodiment of this invention is set forth in the accompanying drawing in the manner following:

Figure 1 is a perspective view showing the watch case closed;

Fig. 2 is a similar view showing the covers of the watch case opened up as in use;

Fig. 3, which is a central longitudinal section through the outer covers with the inner case in side elevation, shows the article opened up as in Fig. 2;

Fig. 4 is a view similar to Fig. 3, the covers being closed, however, as in Fig. 1;

Fig. 5 is a fragmentary sectional detail taken on line 5-5 of Fig. 3; and

Fig. 6 which is a sectional view similar to Figs. 3 and 4, shows the parts opened to a position where in the movement is accessible for inspection or repair.

The present invention is entitled as a "Watch" inasmuch as it includes generally a movement A together with a case B therefor. It also includes therewith a pair of case covers C, the case and covers being peculiarly constructed so as to cooperate in a special manner.

The movement may be accommodated within the usual ring 10 having an interlocking or jointed connection with one of the case components, as, for example, its bezel 11. Associated with such a bezel is a back or lid 12, preferably by a hinge connection 13, as shown. A catch of any approved kind may be employed to hold the back releasably in normal position upon the bezel.

Extended laterally and rigidly from one of the case parts—the back, for example—is a bow 14 between the opposite arms of which is mounted a pin 15 forming a hinge connection with a sleeve or joint 16 that up-stands from an edge of one cover member 17. As shown, the edges of the two covers

55 are flanged inwardly, as at 18, wherein may be formed suitable notches 19 for accommodating the bow arms when the covers are closed, as in Fig. 4. It is to be noted that the outer end of the bow is extended externally of the covers C for an appreciable distance, thus permitting the fingers to take hold thereof in the manner presently to be explained. The hinge connection 15, as shown, may lie just to the outside of the covers C, while the other hinge connection 13 for the case parts is disposed well within the covers.

There is also employed a spring hinge connection 20 between the two covers C. The precise form of the spring means used in this connection is immaterial. If desired, the well known torsional type of hinge pin may be adopted for this purpose. The tension of the spring in this connection is to close the covers—not to open them, as has been the common practice in articles of this character. Also upon the free edge of the case B it is preferred to mount a pair of feet 21, the same being affixed either to the bezel or back so as to rest against the inner side of the second cover member 22 when the parts are opened out as in Fig. 3 where, it will be noted, the case and two covers form a triangle with each angle thereof less than 90°.

80 In the production of a watch as hereinbefore set forth, it is unnecessary to provide any catch for the two covers C. The spring hinge connection 20 tends to hold them closed, thereby making a catch superfluous. At the time it is desired to open the covers, the bow is grasped, as is also the cover member 22, following which the one is pulled away from the other. During this movement the position of the case is entirely under the operator's control, due to his grasp of the bow which is rigidly connected therewith. Accordingly the case may be swung around gently to its final position as shown in Figs. 2 and 3, all without any jar or snap, such as might injure the watch movement. In like manner, the case is swung back against the cover member 17 before the complementary member 22 is allowed to close thereupon. In these movements the feet 21 are brought into contact with the inner side of the cover member 22. It is unnecessary that any guideway be provided for the feet

owing to the tendency of the cover members to close, rather than to open, as has been the common practice heretofore.

A further advantage is realized whenever it becomes necessary to inspect, repair, or renew the watch movement. In the present article, the case may be swung completely out from between the two covers (see Fig. 6) by opening the latter sufficiently for this purpose. When so disposed exteriorly of the covers, the case back may be separated from the bezel, as shown, affording access to the movement or permitting, if desired, the movement to be taken out in its entirety.

This is a feature unknown, so far as I am aware, in other traveler's watches wherein the case must first be removed before the movement can be taken out.

The present watch may be produced with a minimum of expense owing to its elimination of such features as a catch for the covers, a track or guideway in one cover for the case to slide in, a second spring hinge where the case is connected to the covers, etc. With these parts omitted, the construc-

tion is greatly improved in that I have reduced the manufacturing expense, and have provided for complete control over the case at such times as its position between the covers undergoes change, and have also promoted accessibility of the case and movement whenever an inspection is to be made.

I claim:

1. A watch comprising a two-part movement supporting case, a pair of hinged cover members for enclosing or supporting said watch in upright position therebetween, and a common hinge member connecting said case parts and one of said cover members.

2. A watch comprising a two-part movement supporting case, a bow rigidly extending from one case part, a hinge connection between said bow and said other case part, a pair of hinged cover members for enclosing or supporting said watch in upright position therebetween, and a hinge connection between said bow and one of said cover members.
